UNITED STATES PATENT OFFICE.

MURDOCK MCNEIL, OF BOSTON, MASSACHUSETTS, ASSIGNOR TO THE EMPIRE STEAM GAUGE COMPANY, OF SAME PLACE.

PRESSURE-GAGE.

SPECIFICATION forming part of Letters Patent No. 445,355, dated January 27, 1891.

Application filed July 5, 1890. Serial No. 357,840½. (No model.)

To all whom it may concern:

Be it known that I, MURDOCK MCNEIL, of Boston, in the county of Suffolk and State of Massachusetts, have invented certain new and useful Improvements in Steam-Pressure Gages, of which the following is a specification.

This invention relates to pressure-gages in which the spring which actuates the index or pointer is a bent metal tube usually of a flattened or elliptical shape in cross-section. The connection between the gage and boiler is made by a pipe in which the steam is condensed, the water of condensation filling the said spring and receiving the steam-pressure, so that the curvature of the spring varies with the steam-pressure, the movement given the free end of the spring by the variation of its curvature being imparted through suitable mechanism to the indicator or pointer, as shown in the Bourdon patent, No. 9,163.

The invention has for its object to provide improved means for securing to the spring and casing an auxiliary spring which shall supplement the curved spring and prevent the loss of elasticity of the latter from affecting the operativeness of the apparatus; and to this end the invention consists in the improvements which I will now proceed to describe and claim.

In the accompanying drawings, forming a part of this specification, Figure 1 represents a front view of a steam-gage embodying my improvements, the dial-plate being removed. Fig. 2 represents a section on line 2 2, Fig. 1.

The same letters of reference indicate the same parts in all the figures.

In the drawings, A represents the bent metal tube, one end of which is rigidly attached to the casing A' and the other end to a rod B, which is connected at C to a lever D, which is fulcrumed at I and has a toothed segment E at its other end. The latter gears into a pinion F, Fig. 2, on the spindle G of the index or pointer H.

The construction above described in common and of itself forms no part of my invention. When the water is forced up by the steam-pressure into the tube A, the tendency of said tube is to straighten, and thus impart

motion to the segmental lever and through the latter to the index or pointer. When the gage is in good order, the index should always go back to zero when the pressure is removed. It has been found, however, that the spring-tube A has a tendency to lose its elasticity by use, so that the gage is often rendered unreliable.

My invention is intended to remedy the above-mentioned defect, and it is carried into practice as follows:

a represents a spring, preferably helical in form, suitably secured at its outer and inner ends to lugs or nuts b b'. The nut b at the outer end of said spring is adapted to receive a screw c, and the nut b' at the inner end of the spring receives a screw d, having its lower end provided with a slot e to receive an ear f, formed on a clamp g, surrounding the tube A, and secured thereon by a screw h, the arrangement being such that a jointed connection is formed between the tube and spring by a pin i passing through the ear f and screw c, as will be clearly understood by reference to Fig. 2.

j represents a bushing, which is suitably fitted into the casing A' and through which passes the screw c, the latter being provided with a left-hand screw-thread and adjustably secured by jam-nuts k k'.

It is obvious that by means of the screw c the pressure of the spring a on the spring-tube A may be adjusted to any desired extent. It will be seen that the force of the spring a is always exerted to keep the tube in its normal position, or that which it occupies when the pointer H is at zero, and that whenever the steam-pressure operates to vary the curvature of the tube A it must also operate against the spring a, said spring receiving all the pressure and being compressed to an extent corresponding to the displacement of the tube A, so that its force is exerted to compel the tube A to return to the proper point when the pressure decreases.

My improvement can be easily applied to any gage of this class and is not limited to steam-pressure gages.

Another important function of the spring a is to prevent the vibration of the pointer H by the jar of the machinery with which it

is connected. The spring *a* may be of other than spiral form, if preferred, although I prefer the spiral form as the most convenient.

I am aware that an auxiliary spring has 5 been before employed in connection with a Bourdon spring. Hence I do not claim, broadly, the combination of an auxiliary spring with a Bourdon spring.

I claim—

- 10 1. In a pressure-gage, the combination of the casing, the spring-tube *A* therein, the spring *a*, interposed between the casing and the tube, a holder or support for the outer end of said spring, attached to the casing, 15 a clamp attached to the tube, a nut or collar engaged with the inner end of the spring, and a hinge or joint connecting the collar with the clamp, as set forth.

2. In a pressure-gage, the combination of the casing, the tube *A* therein, the spring *a*, 20 interposed between the casing and the tube, the adjusting-screw *c*, engaged with the casing and supporting a nut which is engaged with the outer end of the spring *a*, the clamp *g*, attached to the tube, the nut or collar *b'*, 25 engaged with the inner end of the spring, and the hinge or joint connecting said collar *b'* with the clamp *g*, as set forth.

In testimony whereof I have signed my name to this specification, in the presence of 30 two subscribing witnesses, this 1st day of July, A. D. 1890.

MURDOCK McNEIL.
